UNITED STATES PATENT OFFICE

EDWARD B. HOUGH, OF PROVIDENCE, RHODE ISLAND

CIGARETTE CASE

Application filed September 8, 1927. Serial No. 218,167.

The invention relates in general to containers and more particularly to cigarette cases. In the usual commercial cigarette case, it is sometimes difficult to fill the cigarette case with cigarettes and to dispense the cigarettes from the case without breaking or partially mutilating them. If this objection is not present, then the cigarettes are loosely held within the case and subject to rapid deterioration due to shaking when carried about on the person. Furthermore, the usual cigarette case is either of small capacity or, if the capacity is large, it is comparatively large and bulky. The above disadvantages are overcome by the present invention in a simple and efficient manner and the device of the invention has many additional advantages which will appear as the description proceeds.

According to the invention, the cigarette case is made up of a base cover and a top cover preferably hingedly connected. The base cover preferably has two compartments located in the same plane, each compartment being adapted to hold a single layer of cigarettes. It is therefore only necessary to make the case of sufficient thickness to hold but a single layer of cigarettes and large capacity is obtained by providing the two compartments. Each compartment is provided with a gently inclined, cigarette-dispensing surface by means of which a cigarette may be dispensed by pushing it lengthwise until its end projects beyond the edge of the case. Each compartment may have a suitable spring-pressed holder in such position that the cigarettes may be dispensed without mutilating them, the holders having suitable catch devices so that they may be held in upper or raised position to allow easy filling of the case. These features aid in producing a case of large capacity, one that is easy to fill and to empty, one that will keep the cigarettes in good condition, and yet will be flat and convenient to carry on the person and have a neat and attractive appearance. The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a perspective view of the case in closed position, illustrating the extreme thinness which may be obtained;

Fig. 2 is a plan view of the case in open position;

Fig. 3 is a side elevation of the case in open position showing the holders in their upper position;

Fig. 4 is a section on the line 4—4 of Fig. 2 showing details of construction;

Fig. 5 is a perspective of the middle wall separating the compartments and showing how the holders are mounted thereon;

Fig. 6 is a detail showing the catch construction;

Fig. 7 is a further detail of an element of the catch;

Fig. 8 is a detail section taken on the line 8—8 of Fig. 2, showing the construction of a hinge;

Fig. 9 is a detail section taken on the line 9—9 of Fig. 2, showing the construction of the middle wall and of the catch.

In the following description and in the claims parts will be identified by specific names for convenience, but they are intended to be as generic in their application to similar parts as the art will permit.

Like reference characters denote like parts in the several figures of the drawings.

Referring now to the drawing, the cigarette case according to the invention comprises a top cover 1 and a base cover 2 hingedly connected together. The base cover comprises a bottom 3 of generally rectangular shape and made of sheet metal having its edge beveled as at 4 and turned in to form a bead 5 as shown, and a generally rectangular frame 6.

The frame 6 is made in the form of a continuous upright wall 7 having an inturned

lower flange 8. The sides of the frame are provided with stamped out projections 9 engaging under the inturned edge of the bead 5 when the lower flange 8 seats against the bevel portion 4 to hold the frame 6 and bottom 3 in assembled relation.

The top cover 1 is of a construction similar to that of the bottom 3 and has its edge bent to form a bevel portion 10 and turned in to form a bead 11. The bead 11 on one side has a plurality of recesses 12 for a purpose hereinafter described.

The back side of the frame 6 is provided with two recesses 13 in which are disposed two hinge knuckles 14, the hinge knuckles being riveted to the upright wall 7. The hinge knuckles 14 are disposed in the recesses 12 in the bead 11 and a separate pintle 15 (Fig. 8) is passed through each knuckle and seats in the bead 11 in the top cover and is suitably secured thereto as by solder. One pintle 15 is in the form of a tube through which passes a spring member 16, one end of the spring member being soldered to the top cover and the other end being suitably secured to the base cover as at 16' (Fig. 2). This construction causes the top cover to normally tend to assume an open position.

Secured to each of the transverse side members of the frame 6 is a gently-sloping, cigarette-dispensing ramp or plate 17 extending from the bottom 3 up to the edge of the upright wall 7 and suitably secured in position.

The base cover 2 is divided into two compartments by means of a middle or bridge wall 20. The middle wall is formed of an element bent over on itself and having projecting tongues 20' which fit in holes cut in the upright wall 7 of the front and back members of the frame 6. Disposed within the U-shaped member is a pivot rod 21 on which is pivoted the holders 22 and 23. Each holder is made up of a transverse portion 24 of open construction having at its ends two arms 25; the arms having openings through which the pivot rod 21 passes.

The pivot rod 21 is tubular and through it passes a spring wire 26, the spring wire being connected to the back arm of holder 23 and to the front arm of holder 22. A second spring wire 27 passes within the middle wall outside the pivot rod and connects the other two holder arms of the holders, this construction being clearly shown in Fig. 5.

It will be understood that these springs 26 and 27 are for the purpose of gently and resiliently holding the holders 22 and 23 in position against the cigarettes to keep them from shaking about in the case and from accidentally sliding out of the case when opened. One holder arm of each holder is provided with a projection 28 and the adjoining holder arm of the other holder is provided with a recess 29, each projection engaging its recess to lock the holders in upper position when

raised to fill the case, this position being shown in Fig. 3.

The catch is made up of a U-shaped finger piece 30 and a spring strip 31. The spring strip has a projection 32 which is adapted to engage the inturned edge of the top cover 1 when the case is closed. The spring strip 31 also has openings to accommodate the projections 33 on the ends of the finger piece, the projections being riveted or clinched over to 75 secure the finger piece to the spring member. The spring member 31 is suitably riveted to the upright wall 7 of the front side of the frame 6 as clearly shown in Fig. 6.

In order to fill the case with cigarettes, the 80 holders will be lifted to their upper position where the catch projections 28 and recesses 29 thereon will engage each other, the spring of one holder balancing the spring of the other. Thus the 85 two compartments will be readily accessible and the case can be easily filled with cigarettes. After the case is filled, the catches on the holders will be disengaged and the 90 holders will gently and yieldably hold the cigarettes in their compartments. When it is desired to dispense a cigarette, a cigarette 95 may be engaged at the end adjoining the middle wall and pushed lengthwise, the inclined surfaces 17 allowing the cigarette to ride over the edge of the base cover. The 100 position and resilience of the holders allow this action without any detrimental effect on the cigarettes.

Thus a cigarette case has been provided 100 which is of relatively large capacity and yet which is thin and convenient to carry about the person. The case may be filled with utmost ease and without mutilating the cigarettes in any way. Similarly, the cigarettes 105 may be removed one at a time with utmost ease and without mutilating them. The cigarettes are gently yet firmly held in the case so that they can not be damaged by carrying about on the person. Furthermore, the parts 110 may be made rugged and comparatively inexpensively and the case is easy to assemble. The arrangement is such that the device is not likely to get out of order but will have a long and useful life, giving pleasing and efficient 115 service to the user.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A container comprising a base cover and a top cover separably secured thereto, said base cover having two compartments, each compartment having a holder, spring means 120

- urging said holders against the material contained in said compartments, said holders having catch devices whereby they catch each other in raised positions.
5. 2. A container having two compartments, each compartment having a holder, spring means urging said holders against the material held in said compartments, said holders having catch devices whereby they catch each other in raised positions.
10. 3. A cigarette case comprising a base cover and a top cover separably secured thereto, said base cover having a transverse wall forming two compartments, each compartment having a holder, spring means urging said holders against the cigarettes in said compartments, said holders having a common pivot, said pivot being at the transverse wall, said holders having catch devices whereby they catch each other in raised positions.
15. 4. In a cigarette case, a base cover and a top cover, said base cover having a back edge, front edge and transverse edges connecting said back and front edges, hinge means connecting the back edges of said covers, a transverse wall connecting said back and front edges and dividing said base cover into two shallow, cigarette-holding compartments, the outer transverse edges of said base cover having cigarette-sliding, inclined surfaces and means for holding said cigarettes in said compartments whereby the cigarettes in each compartment extend from said dividing wall to the cigarette-sliding surface of that compartment and the cigarettes of each compartment are arranged in endwise relation to the cigarettes of the other compartment.
20. 5. In a cigarette case, a base cover and a top cover, said base cover comprising a bottom, a separate rectangular frame held in said bottom, said frame having a front side, a back side and transverse sides connecting said front and back sides, the transverse sides of said frame having cigarette-sliding ramps extending from said bottom to the top of said transverse sides, hinge devices connecting the back of said frame and said top cover, a catch on the front of said frame adapted to engage said top cover, a transverse wall connecting said front and back sides forming two compartments, said ramps extending substantially the entire length of said transverse sides from said front side to said back side, said compartments each being adapted to hold a plurality of cigarettes extending from said transverse wall to said ramps respectively, the entire space between front and back sides being available for cigarettes and being open at the top, and a removable holder in each compartment extending from the back side to the front side.
25. 6. In a case for cigarettes and the like, a rectangular base cover and top cover, said base cover comprising a bottom having an annular inwardly extending flange at its edge, a separate upstanding rectangular frame held in said bottom by said flange, said frame having a back wall, front wall and transverse side walls, a cigarette sliding ramp connecting the top of one side wall and said bottom and extending substantially the entire length of said side wall, hinge devices connecting said back wall and top cover, a holder extending across said base cover and spaced from said side walls to hold a plurality of cigarettes in said base cover with their ends at said ramp and extending away therefrom under said holder, and a catch carried by said front wall and adapted to engage said top cover to hold the case closed.
30. 7. In a case for cigarettes and the like, a base cover and a top cover, said base cover comprising a bottom, a separate frame, means securing said frame and bottom together, a cigarette-sliding ramp connecting the top of one side of said frame and said bottom and extending substantially the entire length of said side, means for holding a plurality of cigarettes or the like in said base cover with one end at said ramp and extending away therefrom, said means extending across said base cover and supporting said cigarettes between the ends thereof and cooperating means on said frame and top cover to hold the case closed.
35. 8. In a cigarette case, a base cover and a top cover, said base cover comprising a bottom, a separate rectangular frame held in said bottom, one side of said frame having a cigarette-sliding ramp connecting the top of the frame and said bottom, hinge devices connecting said frame and said top cover.
40. 9. In a cigarette case, a base cover and a top cover, said base cover comprising a bottom, a frame held in said bottom, hinge means connecting said frame and top cover, said frame having an upstanding wall, said wall having a notch, a catch bar having a projecting catch tongue disposed in said notch, said bar disposed behind said wall and riveted thereto at each end, said wall having spaced apertures, a finger piece having spaced prongs passing through said apertures and secured to said bar, said top cover having a flange over which said catch tongue is adapted to engage.
45. In testimony whereof I have hereunto set my hand.
- EDWARD B. HOUGH.
